Arnold F. Glass

Attorney

UNITED STATES PATENT OFFICE.

ARNOLD F. GLASS, OF BIRMINGHAM, ALABAMA.

GAS STOVE.

Application filed January 20, 1923, Serial No. 613,916. Renewed December 20, 1923.

To all whom it may concern:

Be it known that I, ARNOLD F. GLASS, a citizen of the United States of America, residing at Birmingham, in the county of 5 Jefferson and State of Alabama, have invented certain new and useful Improvements in Gas Stoves, of which the following is a specification.

My invention relates to a new and useful 10 improvement in gas stoves, having for its object to design a stove which is comparatively inexpensive in construction, in which maximum efficiency is obtained from the heat of combustion of gas burners disposed 15 under a closed top having removable stove lids.

A further object of my invention is to increase the economy of operation of the stove by providing in addition to the main large 20 burners in the fire chamber, a smaller supplemental gas burner disposed in the flue between the top of the oven and the top of the stove and in line with an eye, which supplemental burner is adapted to supply heat 25 for a cooking vessel in the eye and additionally to keep the oven hot when it is not desired to utilize the main burners.

My invention also comprises other novel 30 details of construction and arrangements of parts which are hereinafter more particularly described in the following specification and set forth in the appended claims, reference being had to the accompanying drawings, in which:—

35 Fig. 1 is a vertical longitudinal cross-sectional view through the stove.

Fig. 2 is a horizontal cross-sectional view taken on the line 2—2 of Fig. 1.

Similar reference numerals refer to similar 40 parts throughout the drawings.

It being the object of my invention to attain the advantageous results in mind by the simplest, most durable and least expensive construction, I have shown a typical gas 45 stove embodying my invention comprising a rectangular sheet metal body 1 having a top marginal flange 2 and a bottom 3. The stove has an opening 4 in its bottom below the fire chamber 5, which is shown disposed between 50 the left hand end wall and a vertical transverse partition 6 which forms the left hand end wall of the oven 7 and extends from the front wall 8 to the back wall 9 of the stove and is suitably connected thereto and to the 55 bottom 3. This wall 6 serves with the horizontal and vertical partitions 10, 11 and 12

to form the four walls which define the oven 7, and said partitions are so spaced from the stove walls as to form a flue comprising a top portion 13 leading from the fire chamber 60 over the oven to a down flue portion 14 which enters a bottom flue portion 15 returning below the oven to the partition 6. The bottom oven wall 12 in its front corner adjacent to the wall 6 has a series of holes or heat 65 openings 16 which are formed in a perforated section which is preferably not integral with the bottom, but, as shown in Fig. 2 is formed by a separate plate 17 detachably connected to the bottom 12 by bolts or by 70 catches 36 which can be operated to readily release the plate so that it can be removed. I provide a stack or flue 19 which is suitably connected to the back wall 9 of the stove and extends from top to bottom thereof, said 75 flue being in register with a slot or heat outlet opening 20 in the back wall of the oven, and also a lower slot or heat outlet 21 at the left hand end of the flue 15 below the oven. The flue at its upper end is adapted to connect to an ordinary stove pipe or stack 22. I provide sliding dampers 23 and 24 registering respectively with the openings 20 and 21 and connected together by a strap or bar 25. Both dampers are adapted to be operated by the single rod 26 which rises above 80 the top of the stove and has a series of teeth or shoulders 27 thereon which will engage the stove top 28 and hold the dampers in set position. The dampers are of such size and 85 90 so connected that when either is fully open the other is fully closed and vice versa.

The stove top 28 is preferably formed as a casting having the customary stove eyes 29 therein closed by removable lids 30 and 95 100 it is suitably bolted or connected to the body flanges 2. The stove is supported by suitable legs 31 and is provided with main burners 32 preferably extending approximately from front to rear of the stove and 105 disposed in the upper portion of the fire chamber 5. In addition to these burners I provide a supplemental burner 33 located in the flue 13 above the oven and disposed immediately below a stove eye 29. 105

In the front wall of the oven is a hinged door 34. The burners 32 and 33 are preferably connected to the gas main 35 through the front wall of the stove and have the usual air and gas control elements which 110 need not be described.

In operation, having assembled the stove

in the manner described, for ordinary cooking purposes where it is desired to use a number of the eyes to cook on top of the stove and in addition to use the oven, the main burners 32 are used, the products of combustion therefrom rising and passing to the right through the flue 13 above the oven and down flue 14 at the right of the oven and back forward through flue 15 towards the front left hand corner of the oven and thence passing up through the perforations 16 in the oven bottom 17 and through outlet 20 to the stack. If outlet 20 is closed and outlet 21 is open, the heat 10 will be diverted from the oven and will flow under the oven to the outlet 21 and thence up the stack. In intermediate positions the dampers 23 and 24 regulate the exact amount of heat desired to be passed through the oven. By removing plate 17 the bottom flue 15 can be cleaned of all matter that may collect therein.

Having thus described my invention, what I claim as new and desire to secure 25 by Letters Patent, is:—

1. A gas burning stove having at one side a fire chamber with gas burners therein, a closed top for the stove having removable lids, partitions forming within the stove an oven, the partitions being spaced from the top and bottom walls and the end wall of the stove remote from the fire chamber to form a flue about the oven, the partition adjacent to the fire box being extended to 30 meet the bottom wall, a plurality of heat

inlet ports disposed in the forward corner of the oven bottom adjacent to the fire chamber, a stack having heat outlets leading from the oven and from the flue below the oven, and damper means to control said outlet ports. 40

2. A gas stove in accordance with claim 1, in which the heat ports in the oven bottom are formed in a removable plate forming 45 part of the bottom.

3. A gas burning stove comprising a closed top provided with removable lids and a bottom, vertical and horizontal connecting partitions in the stove body which define therein an oven spaced from the top, bottom and end walls of the body, a fire chamber at one side of the oven having large capacity gas burners therein, a small supplemental gas burner arranged in the space 50 above the oven and disposed under one of the removable top lids, a partition interposed between the flue space below the oven and the fire chamber, a plurality of heat ports opening through the bottom of the oven, a stack having a connection with the flue space below the oven and with the upper portion of the oven, and damper means to regulate the admission of the products of combustion through said ports to 55 the stack. 60

In testimony whereof I affix my signature.

ARNOLD F. GLASS.
